(57) **CLAIM**

The ornamental design for a baluster, as shown and described.

DESCRIPTION

FIG. 1 is a left-side perspective view of a baluster showing my new design.

FIG. 2 is a right-side perspective view thereof.

FIG. 3 is a front view thereof.

FIG. 4 is a rear view thereof.

FIG. 5 is a left-side view thereof.

FIG. 6 is a right-side view thereof.

FIG. 7 is a top view thereof; and,

FIG. 8 is a bottom view thereof.

The broken lines shown in FIGS. 1-5 and FIGS. 7-8 illustrate portions of the baluster that form no part of the claimed design.
